NATURAL MOTIFIC OIL

UNIFORMITY.—By a mechanical process, this Oil is rendered free of all silicious particles, imprisoned water, and glutinous or parafinous deposits.

SAFETY.—Does not congeal in any Temperature, absolutely unchangeable from exposure, and thus as an anti-friction agent, produces economical results.

PURITY.—Superior to animal, vegetable or compounded Oils, being free of all acrids and acids, and retaining its Purity for all time.

LUBRICITY.—Cleanses Machinery of gums and residuum left by use of inferior Oils, thus preserving it from injury, rust or friction.

UTILITY.—Pure and unadulterated.

UTILITY.—Pure and unchanging in character, free of all injurious constituents, is adapted to the most delicate parts of clocks and watches, as well as to the most ponderous boxes and journals of the heaviest machinery.

**TO PREVENT SUBSTITUTION OR COUNTERFEITING, ALL PACKAGES
ARE SEALED.**

MoFarrell

United States Patent Office.

JOHN FARRELL, OF BALTIMORE, MARYLAND.

Design No. 3,385, dated February 23, 1869.

DESIGN FOR A TRADE-MARK.

The Schedule referred to in these Letters Patent and making part of the same.

To all whom it may concern:

Be it known that I, JOHN FARRELL, of Baltimore, in the State of Maryland, have originated a new Design for a Label, which is correctly represented in the accompanying print, forming a part of this specification.

The label is intended for various uses.

The reading-matter forms no necessary part of the design, and may, of course, be changed at pleasure, without departing from my invention.

I claim as new, and desire to secure by Letters Patent—

The design for a label, substantially as herein represented.

JNO. FARRELL.

Witnesses:

F. H. ANGIER,
L. B. CLARK.
